[57] CLAIM

The ornamental design for a bottle or the like, as shown and described.

DESCRIPTION

FIG. 1 is a front perspective view of a bottle or the like showing my design;

FIG. 2 is a front elevational view thereof;

FIG. 3 is a top plan view thereof;

FIG. 4 is a bottom plan view thereof;

FIG. 5 is a fragmentary sectional view thereof taken along the line 5—5 of FIG. 4;

FIG. 6 is a front perspective view showing a modified form of my new design;

FIG. 7 is a front elevational view thereof;

FIG. 8 is a top plan view thereof;

FIG. 9 is a bottom plan view thereof; and

FIG. 10 is a fragmentary sectional view thereof taken along the line 9—9 of FIG. 9.

The dominant feature of my design resides in the series of spaced circumferentially extending raised ribs on the inwardly tapered upper part of the container.
